[57] CLAIM

The ornamental design for an automotive rear seat protector, as shown and described.

DESCRIPTION

FIG. 1 is a top, front, and left side perspective view of an automotive rear seat protector showing our new design, the broken-line disclosure of an automobile rear seat being for illustrative purposes only and forming no part of the claimed design;

FIG. 2 is an enlarged top plan view thereof;

FIG. 3 is an enlarged rear elevational view thereof;

FIG. 4 is an enlarged bottom plan view thereof; and,

FIG. 5 is an enlarged right side elevational view thereof.

FIG. 1

FIG. 5

FIG. 2

FIG. 3

FIG. 4
